VEHICLE WASHING APPARATUS

Louis D. Holmes, Blue Island, Ill., assignor to
 Whiting Corporation, Harvey, Ill., a corporation
 of Illinois

Application July 31, 1943, Serial No. 496,879

5 Claims. (Cl. 15—53)

The invention relates to washing apparatus for vehicles and more particularly to that type of apparatus for washing railway cars or other vehicles while they are moved past and engage motor driven vertical rotary brushes.

One object of the invention is to provide simple and efficient means for pivotally supporting the brush for horizontal swinging and pressing it against the side of the vehicle during the washing and automatically retracting it to a central position after the vehicle has traveled past the brush.

Another object of the invention is to provide improved means for this purpose which requires only a single weight and cable for permitting the deflection of the brush horizontally in opposite directions from its central position by a vehicle traveling in either direction and retracting it to its central position when the vehicle has traveled past the brush.

Another object of the invention is to provide washing apparatus which comprises a spray pipe for the rotating brush and a supporting structure for pivotally supporting the brush and spray pipe for horizontal swinging movement in opposite directions from a central position, and means for causing the brush to be pressed against the side of the vehicle and retracted to its central position through engagement with the spray pipe.

Another object of the invention is to improve the construction set forth in Patent No. 2,318,995.

Other objects of the invention will appear from the detailed description.

The invention consists in the several novel features which are hereinafter set forth and more particularly defined by claims at the conclusion hereof.

In the drawings:

Fig. 1 is a front elevation of washing apparatus embodying the invention.

Fig. 2 is a vertical section taken on line 2—2 of Fig. 1.

Fig. 3 is a horizontal section taken on line 3—3 of Fig. 1.

Fig. 4 is a vertical section taken on line 4—4 of Fig. 1.

Fig. 5 is a rear elevation of one of the devices for yieldably shifting a brush.

Fig. 6 is a perspective of the lower portion of the supporting structure for one of the brushes.

The invention is exemplified in washing apparatus which comprises a central upright I-beam which constitutes a rigid supporting mast 10, a vertical rotary brush 11 of sufficient height

to traverse and wash the entire side of a vehicle and a short vertical rotary brush 12 adapted to wash the windows of the vehicle. Each of the brushes is supported by a structure which comprises a pair of arms which are pivoted to swing horizontally to permit the brushes to be contacted by the side of the vehicle and deflected laterally in either direction from a central position in which it projects into the path of travel of the vehicle. A weight actuated device is provided for each brush to press the brush against the vehicle and automatically retract it to its central position.

The supporting structure for the brush 11 and its shaft 14 comprises an upper supporting arm 17, the distal end of which carries a self-aligning bearing 16 for shaft 14; a vertically extending spacer tube 23 rigidly secured to arm 17; a shaft 25 extending through tube 23 and having its upper end journaled in a bearing 26 fixed to a bar 27 which is welded to the mast 10 and its lower end journaled in a bearing 28 fixed to a bar 29 which is welded to the mast 10; and a lower arm 31 which is pivoted on the shaft 25 supported on a thrust bearing 32, and carries at its distal end a self-aligning bearing 30 for the lower end of brush shaft 14. An arm 33 is rigidly secured to the lower end of tube 23 and is provided with a fork 35. An abutment 34 which extends through the arm 31 has a limited horizontal movement in the fork 35 to permit the brush 11 and its shaft 14 to tilt laterally so that the brush will be free to align itself with the vehicle side when the vehicle is tilted and its side is not vertical. A spray-pipe 41 extends between the upper arm 17 and the lower arm 31 and is provided with nozzles 42 for spraying water on the rotating brush 11. A clevis-fitting 43 connects the lower end of spray-pipe 41 to the abutment 34 and the upper end of pipe 41 is connected by a clevis 46 to the same arm 17. The clevises 43 and 46 permit the spray-pipe 41 to follow the angular movement of the brush 11 when it aligns itself with the tilted vehicle side. The fork 35 limits the angular movement of the brush 11 and spray-pipe 41 and the angular movement of shaft 14 in its upper bearing 16.

The supporting structure for the brush 12 and its shaft 15 comprises an upper arm 17 which carries at its distal end a bearing 16, a lower arm 37 which carries the bearing 36 on the lower end of brush shaft 15, a spacer tube 24 fixedly secured to said arms 17 and 37, a shaft 38 extend-

ing through the spacer tube 24, an upper bearing 26 for shaft 24 which is welded to the bar 27, and a lower bearing 39 which is welded to the bar 40 and in which shaft 24 is journaled. A spray-pipe 41 extends between the upper supporting arm 17 for the shaft 15 and the lower supporting arm 37 for said shaft. This spray-pipe is provided with nozzles 41' for spraying water onto the rotating brush 12. The upper end of spray-pipe 41 is connected by a clevis 46 to the arm 17 which supports the shaft 15 and its lower end is connected by a clevis 48 to the lower arm 37.

A separate driving mechanism is provided for each of the brushes for individually driving said brush shafts. Each driving mechanism comprises a vertical electric motor 18 supported on the top of a bracket 19 which is rigid with and is adapted to swing with one of the arms 17; a small belt pulley 20 on the depending shaft of the motor; a series of endless belts 21 driven by pulley 20 and a belt pulley 22 driven by the belts and secured to the upper end of each of the brush shafts 14, 15.

Stationary vertical jet pipes 49 and 50 which are connected together by a pipe 51 are adapted to direct streams of water against the side of the vehicle as it is approaching and after it has passed the brushes. A flexible pipe 52 supplies water from pipe 51 to the jet pipe 41 and a flexible pipe 53 supplies water from pipe 51 to the jet pipe 47. Spray shields 54 and 55 are secured to the mast 10 to confine the splash from the brushes so it will not be projected outwardly of the mast 10.

A weight actuated device is connected to each of the brushes for normally holding them respectively in a central position, for yieldingly pressing the brush against the vehicle side when it is deflected in opposite directions by the vehicle, and for retracting the brush when the vehicle has passed through the brush. These devices are substantially alike in construction and each comprises a rotatable member 56 around one of the spacer tubes 23 or 24, and vertically supported thereon by a collar 57 which is secured to the tube by a set-screw; a weight 59 of sufficient force to shift the brush and its supporting structure and guided vertically in a cylinder 59' which is welded to a flange on the bar 29; a cable 58 from the lower end of which the weight 59 is suspended; a stud 60 which is provided with a pintle 61 which is journaled in the rim of member 56 and which is provided with a socket in which the expanded upper end of the cable is fixedly secured; and a pair of sheaves 62 between which the cable 58 is guided beneath the stud 60. Each member 56 is provided with a fork 69 which straddles one of the spray-pipes 41, 47 to provide a connection between said member and one of the brush supporting structures. When a brush is swung horizontally in either direction from its normal position, the spray-pipe carried by its supporting structure will rotate member 56 and stud 60 will be shifted horizontally around the axis of the spacer tube of that structure as illustrated by dotted lines in Fig. 5. This movement of stud 60 will lift the weight 59 while the portion of the cable between sheaves 62 and the stud will be pulled angularly and laterally to lift the weight 59 so that the force of the weight will be exerted to rotate member 56 to shift the supporting structure for said brush through the engagement of fork 69 with one of the spray-pipes 41, 47. The weight 59 will then function to press the brush against the vehicle. In this construction, the spray-pipes 41, 47 function as vertical connec-

tions between the upper and lower brush supporting arms, which are laterally offset from the vertical spacer tubes which are coaxial with the arms, and are connected to the members 56 for conjoint horizontal swinging movement.

When the vehicle has traveled past the brush, the weight will retract the rotatable member 56 and the latter, through its engagement with the spray-pipe 41 or 47, will retract the brush to its normal or central position. When the brush 11 is deflected by the vehicle and is inclined for alignment with the tilted side of the vehicle, the arm 31 within the limits permitted by abutment 34 and fork 35 will be movable relatively to the upper supporting arm 17 of the supporting structure for said brush. When this occurs, the rotatable member 56 through fork 69 and spray-pipe 41 by the force of the weight 59 connected to said member, will shift the brush 11 from its inclined position to its vertical and normal or central position by the engagement of member 56 and the spray-pipe 41. In this operation arm 33 will swing with the upper arm 17 and the lower supporting arm 31 for brush 11 will be shifted by member 56 and the spray-pipe 41 so its abutment 34 will be centered in the fork 35. The member 56 is preferably formed of plate metal and comprises a plate 65, a rim 66 welded to plate 65, a collar 67 welded to plate 65, and ribs 68 welded to plate 65, collar 67 and the rim 66. The pintle 61 of stud 60 is journaled in a block 70 which is welded to the rim 66 and plate 65 and secured in said block by a pin 71. Each sheave 62 is journaled in a forked bracket 63 which is secured to a bar 64 which is welded to the mast 10.

The operation of the apparatus will be as follows: The vehicle or railway car to be washed will be moved to travel past the washing unit and as it reaches the brushes 11, 12 it will deflect them in the direction of travel of the vehicle and swing their supporting structure horizontally. Each structure will, through the connection between the spray-pipe connected thereby between its upper and lower supporting arms, rotate one of the members 56. Such rotation of each member 56 will pull the end of the cable 58 attached to the stud 60 which is swivelled to swing on a horizontal axis in said member. The stud moves accurately and horizontally according to the direction in which the extent to which the brushes are swung. The stud 60 will shift cable 58 to raise the weight 59 for pressing the brush against the side of the vehicle. The stud 60 during the rotation of member 56, will rotate in said member to cause a direct pull on the cable between the guide sheaves 62 and the stud. As the vehicle moves past the brushes the rotating brushes sprayed with water will wash the vehicle. The spray-pipes 49 and 50 will spray the vehicle with water before and after the vehicle travels past the brushes. As soon as the vehicle has passed the brushes, the force of the weights 59 will react on the members 56 and the latter will, through the engagement with the spray-pipes 41, 47, respectively, restore the brushes to their central positions in readiness for washing a succeeding vehicle. When the brush 11 is inclined from its vertical position as it aligns itself with a tilted car side, the lower supporting arm 31 will move relatively to the upper supporting arm 17 for the brush 11 and correspondingly incline the spray-pipe 41 from its normal and vertical position. When this occurs, the force of the weight 59 will, through cable 58 and member 56, react on the spray pipe 41 to restore the brush

11 to its normal vertical position after the brush is released by the vehicle. This insures the return of the brush 11 to its normal vertical position at all times.

The invention exemplifies a device actuated by a single weight for pressing one of the brushes against the vehicle and which automatically restores the brush to its normal central position. The invention also exemplifies a weight actuated means for these purposes which is simple in construction and efficient in operation.

Having thus described the invention, what I claim as new and desire to secure by Letters Patent is:

1. In a vehicle washing apparatus, the combination with a vertically extending rotary motor-driven brush adapted to engage one side of the vehicle and a brush-supporting structure pivoted for deflection horizontally in opposite directions from a normal central position by the engagement of the vehicle with the brush, of a member on the axial portion of the structure and for horizontal swinging movements therewith, a stud swiveled in said member to rotate in a plane transverse to the swinging movements of the member, a weight for retracting the structure and the brush, a cable having one of its ends fixedly secured to the stud and its other end connected to the weight, for lifting the weight when the brush is shifted in opposite directions from its central position for automatic retraction of the brush to its central position by the weight from its off-center positions, and stationarily supported guide means for and on opposite sides of the cable and closely adjacent the stud.

2. In a vehicle washing apparatus of the character described, the combination with a vertically extending rotary motor-driven brush adapted to engage one side of the vehicle and a brush-supporting structure pivoted for deflection horizontally in opposite directions from a normal central position by the engagement of the vehicle with the brush, of a member having an arcuate substantially concentric peripheral face and on the axial portion of the structure, and for horizontal swinging movements therewith, a stud swiveled in said member to rotate in a plane transverse to the swinging movements of the member and projecting from said peripheral face, a weight for retracting the structure and the brush, a cable having one of its ends fixedly secured to the stud and its other end connected to the weight, for lifting the weight when the brush is shifted in opposite directions from its central position for automatic retraction of the brush to its central position by the weight from its off-center positions, and stationarily supported guide means for and on opposite sides of the cable and adjacent the stud and the peripheral face of said member.

3. In a vehicle washing apparatus of the character described, the combination with a vertically extending rotary motor-driven brush adapted to engage one side of the vehicle and a brush-supporting structure pivoted for deflection horizontally in opposite directions from a normal central position by the engagement of the vehicle with the brush, of a member having an arcuate substantially concentric peripheral face and

on the axial portion of the structure, and for horizontal swinging movements therewith, a stud swiveled in said member to rotate in a plane transverse to the swinging movements of the member and projecting from said peripheral face, a weight for retracting the structure and the brush, a cable having one of its ends fixedly secured to the stud and its other end connected to the weight for lifting the weight when the brush is shifted in opposite directions from its central position for automatic retraction of the brush to its central position by the weight from its off-center positions, and a pair of guide-sheaves supported to rotate on stationary axes on opposite sides of the cable, respectively, and adjacent the stud and the peripheral face of said member.

4. In a vehicle washing apparatus of the character described, the combination with a vertically extending rotary motor-driven brush adapted to engage one side of the vehicle and a brush-supporting structure pivoted for deflection horizontally in opposite directions from a normal central position by the engagement of the vehicle with the brush, of a member having an arcuate substantially concentric peripheral face and on the axial portion of the structure and for horizontal swinging movements therewith, a stud swiveled in said member to rotate in a plane transverse to the swinging movements of the member and projecting from said peripheral face, a weight for retracting the structure and the brush, a cable having one of its ends fixedly secured to the stud and its other end connected to the weight for lifting the weight when the brush is shifted in opposite directions from its central position for automatic retraction of the brush to its central position by the weight from its off-center positions, and a pair of guide-sheaves supported to rotate on stationary axes on opposite sides of the cable, respectively, and adjacent the stud and the peripheral face of said member.

5. In a vehicle washing apparatus of the character described the combination with a vertically extending rotary motor-driven brush adapted to engage one side of the vehicle and a brush-supporting structure pivoted for deflection horizontally in opposite directions from a normal central position by the engagement of the vehicle with the brush, of a member having an arcuate substantially concentric peripheral face and on the axial portion of the structure for horizontal swinging movements therewith, a stud swiveled in said member to swing in a plane transverse to the swinging movements of the member and provided with an eye projecting from said peripheral face, a weight for retracting the structure and the brush, a cable having one of its ends fixedly secured in said eye on the stud and its other end connected to the weight for lifting the weight when the brush is shifted in opposite directions from its central position for automatic retraction of the brush to its central position by the weight from its off-center positions, and guide-means for and on opposite sides of the cable, respectively, and supported adjacent said eye and the peripheral face of said member.

LOUIS D. HOLMES.
